Attorney

UNITED STATES PATENT OFFICE.

HARRELL C. TAYLOR, OF SEALEVEL, NORTH CAROLINA.

OYSTER-DREDGE.

1,323,122.

Specification of Letters Patent. Patented Nov. 25, 1919.

Application filed June 6, 1919. Serial No. 302,272.

To all whom it may concern:

Be it known that I, HARRELL C. TAYLOR, a citizen of the United States, residing at Sealevel, in the county of Carteret and State 5 of North Carolina, have invented certain new and useful Improvements in Oyster-Dredges, of which the following is a specification.

This invention is an oyster dredge and 10 has for its principal object the production of a device which may be placed on the bed of a stream and propelled by any suitable power, and under such conditions will dig oysters from an oyster bed and will efficiently cull the small oysters from the large 15 oysters allowing the smaller oysters to be dropped back into the bed, while the larger oysters will be conveyed back into a receiving receptacle.

20 Another object of this invention is the production of an oyster dredge wherein a plurality of rotating agitators are provided which will efficiently cull the oysters passing thereover, these agitators being of such construction as to move the larger oysters rearwardly, the oysters also passing over gratings through which the smaller oysters may fall, the oysters then being finally deposited 25 within a receptacle where they may be removed from, when desired.

One practical form of construction and assembly of the present invention will be hereinafter described and is illustrated in the drawing, in which:—

30 Figure 1 is a side elevation of the oyster dredge constructed in accordance with the present invention, a portion of the receiving receptacle being broken away.

Fig. 2 is an enlarged sectional view taken 40 on the line 2—2 of Fig. 3.

Fig. 3 is an enlarged horizontal section through the forward portion of the dredge.

In the preferred embodiment of the present invention, about to be specifically described, the scoop and assorting portion of the dredge comprises a pair of parallel side walls 5 having sleeves 6 at their upper and lower edges in which strands 7 are carried, the forward ends of the strands being provided 45 with eyes whereby links 9 connected to a draw bar or cable 10 are secured, thus allowing the dredge to be connected to a boat or other towing means, thus permitting the dredge to be dragged along the bottom

of the stream or body of water for operating in its correct manner.

The bottom of the receptacle is of solid material 11 although the lower strands 7 are carried thereby, thus connecting the receptacle to the scoop and assorting portion 50 of the dredge. The upper strands 7 may also extend rearwardly, thus permitting the side walls 12 of mesh, to be connected to the bottom and also to the upper strand to form an inclosed receptacle. The rear end of the receptacle may be closed by a suitable form of gate 13, whereby after the same has been filled it may be easily emptied as desired. It should be noted that the forward end of the bottom 11 is curved upwardly as shown 55 at 11' thus allowing the bottom 11 to ride evenly over small oysters which may be culled and discharged from the larger oysters and also allow the bottom 11 to ride 60 easily over an uneven surface of the bottom 70 of the stream or body of water in which the dredge is being operated.

A bar 14 is carried by the forward portion of the side walls 5 adjacent the lower portions thereof as shown in Fig. 2 and has 65 the forwardly extending parallel claws projecting therefrom and slanting downwardly. Therefore the claws will dig into an oyster bed and cause the oysters to slide upwardly therealong as the dredge moves 75 forwardly. An inclined grating comprises 80 a pair of end strips 16 fixed upon the inner surfaces of the side walls 5 and connected together by transversely extending rods 17 reinforced intermediate their ends by similar strips 16'. As the rods 17 are spaced apart in any desired distance, it is obvious 85 the passing of oysters thereonto the forward ends of the claws 15 will cause the oysters which are being forced upwardly along the 90 claws to be forced onto the grating, the smaller oysters being allowed to fall through the space between the rods 17. The continued movement of oysters up over the claws 15 will continue to force the larger 95 oysters rearwardly beyond the forward 100 grating.

A pair of drive shafts 18 are carried by the side walls 5 and have enlarged drive wheels 19 on their outer ends, these spurred 105 drive wheels engaging the bottom of the stream to cause rotary motion to be imparted to the shafts 18 as the dredge moves

forwardly. Other shafts 20 are journaled in the side walls 5 parallel to the driving shafts 18 and these last mentioned shafts 20 have radiating fingers 21 extending therefrom as shown in Figs. 2 and 3. Each pair of shafts 20 have gears 22 keyed thereon and meshing with similar gears 23 keyed upon the drive shafts 18. Therefore, although the drive shafts 18 will rotate forwardly the finger shafts 20 will be rotated rearwardly. Two such series as described are herein illustrated, although it is obvious that any number desired can be employed without departing from the spirit of the present invention. The grating at the forward end of the scoop and assorting device direct the larger oysters onto the forward shaft and fingers thereof above the shaft as shown in Fig. 2. As these shafts will be rotated rearwardly, the fingers will throw the oysters rearwardly, it being noted that the fingers are spaced apart at a sufficient distance to allow the smaller oysters to fall therebetween. The movement of the larger oysters rearwardly however, will progress owing to the fact that the oysters will be fed along toward the rear portion of the scoop from one fingered shaft to the next until they are finally deposited upon the downwardly slanting grating at the rear end of the scoop and contiguous to the forward end of the receptacle. This grating comprises end strips 24 connected by transversely extending rods 25 reinforced by strips 24' intermediate their ends. The oysters which will slide across and downwardly along the rear grating will be deposited within the interior of the receptacle. It will be noted that when the device is in use, it is placed upon the bottom of a stream and may then be pulled or propelled forwardly in any desired manner. The claws 15 will sink down into the oyster bed, causing the large and small oysters alike to be elevated and pushed rearwardly therealong and over the forward upwardly inclined grating. It is true that some of the small oysters may fall through this grating 16, although a greater portion of the oysters will be passed from this grating onto the rearwardly rotating fingers 21. The movement of these fingers will further cause the oysters to be further agitated and as the fingers are moving beneath the water it is obvious mud will be washed from the selected oysters, while the smaller oysters will slip between the fingers and fall back into the bed of the stream. The larger oysters will be thrown rearwardly and finally will pass over the rods 25 of the rear downwardly slanting grating and will finally be deposited within the receptacle where they are retained until finally removed. Thus oysters in original condition may be lifted from the bed of the stream but before being

deposited within the receptacle will be assorted, the smaller oysters being dropped back into the stream while the mud will be washed from the larger oysters. As the forward end of the bottom 11 of the receptacle is curved upwardly, the receptacle will easily ride over the smaller oysters which are dropped back into the bed of the stream as specified.

As above stated the number of fingers 75 on the shaft is an immaterial matter, for it may be spaced apart sufficiently to allow comparatively large oysters to fall therebetween or may be sufficiently close together to allow the smaller ones to be so assorted 80 and discharged. The same is true also of the forward and rear grating. As above stated however, it will be seen that a very simple and efficient oyster dredge has been provided which may be positioned in the 85 bed of a stream and may be easily propelled under such conditions to efficiently lift oysters and move the same rearwardly toward the receptacle during such operation efficiently washing the oysters and discharging the smaller ones so that only the larger oysters in a clean condition will be deposited within the receptacle.

The foregoing description and the drawings have reference to what may be considered the preferred, or approved form of my invention. It is to be understood that I may make such changes in construction and arrangement and combination of parts, materials, dimensions, et cetera, as may prove 100 expedient and fall within the scope of the appended claims.

Having thus fully described my invention, what I claim as new and desire to secure by Letters Patent is:—

1. In a device of the character described, the combination of a scoop, a digging means in said scoop, a conveying and assorting means within said scoop which will also agitate oysters to wash the same as the same are moving within the scoop and a receptacle at the rear end of said scoop.

2. In a device of the character described, the combination of a scoop having a digging means at its forward end, gratings carried at the forward end of the scoop adjacent the digging means, and also adjacent the rear end thereof, a receptacle connected to said scoop adjacent the rear end of the rear grating, and an agitating and assorting means carried by said scoop between said gratings.

3. In a device of the class described, the combination of a scoop including a pair of parallel side walls, a receptacle connected to the rear ends of said walls and including an upturned bottom, digging claws extending from the forward end of said walls, an upwardly inclined grating extending from the rear end of said claws and including spaced rods, an inclined grating adjacent the rear

ends of said walls, parallel shafts carried by said walls, means for driving a plurality of said shafts, gears on all of said shafts for connecting the shafts together, whereby all 5 the shafts may be simultaneously rotated, and radiating fingers extending from a plurality of the shafts, whereby oysters dug by said claws will be carried over the forward grating and deposited upon said fingers 10 where they will be agitated to allow the small ones to fall between the fingers and the large ones will be moved rearwardly and be washed, the large oysters being finally deposited on the rear grating to slide down- 15 wardly to the receptacle.

4. In a device of the character described, the combination of a scoop having a digging means at its forward end, an upwardly inclined grating at the forward end of the 20 scoop in the rear of said digging means, a downwardly inclined grating at the rear end of said scoop, a receptacle connected to said scoop adjacent the rear grating, and an agitating and assorting means carried by said 25 scoop between said gratings.

5. In a device of the class described, the combination of a scoop including a pair of parallel side walls, a receptacle connected to the rear ends of said walls, digging claws 30 extending from the forward ends of said walls, an upwardly inclined grating extending from the rear end of said walls and including spaced rods, an inclined grating adjacent the rear ends of said walls, parallel 35 shafts carried by said walls, means for driving a plurality of shafts, gears on all of said shafts for connecting the shafts together, whereby all the shafts may be simultaneously

rotated, and radiating fingers extending from a plurality of shafts, as and for the 40 purposes set forth.

6. In a device of the class described, the combination of a scoop including a pair of parallel side walls, a receptacle connected to the rear ends of said walls, digging means 45 at the forward ends of said walls, an upwardly inclined grating extending from the rear of said digging means and including spaced rods, an inclined grating adjacent the rear ends of said walls, parallel shafts carried by said walls, means for driving a plurality of said shafts, gears on all of said shafts for connecting the shafts together, whereby all shafts may be simultaneously rotated, radiating fingers extending from 50 said shafts, as and for the purposes set forth.

7. In a device of the class described, the combination of a scoop including a pair of parallel side walls, a receptacle connected to the rear ends of said walls, digging means at 60 the forward ends of said walls, an upwardly inclined grating extending from the rear end of said digging means and including spaced rods, an inclined grating adjacent the rear ends of said walls, parallel shafts carried by 65 said walls, radiating fingers extending from said shafts, and means for simultaneously rotating said shafts, as and for the purposes set forth.

In testimony whereof I affix my signature 70 in presence of two witnesses.

HARRELL C. TAYLOR.
